CLAIM

The ornamental design for an oven as shown and described.

DESCRIPTION

FIG. 1 is a top, front perspective view of an oven showing our new design;

FIG. 2 is a front side view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The dash-dot broken lines illustrate the bounds of the claimed design and form no part of the claimed design. The dashed broken lines illustrate portions of the oven that form no part of the claimed design.

1 Claim, 7 Drawing Sheets(56)
